UNITED STATES PATENT OFFICE.

WILLIAM G. ADAMS, OF ROANOKE, VIRGINIA.

SAFETY RAZOR.

Application filed September 26, 1923. Serial No. 664,972.

My improvement relates to a safety razor structure wherein provision is made for conveniently turning the blade so as to bring first one side and then the other side 5 of the blade against the face during the shaving operation, whereby the blade may longer be kept in cutting condition.

Structures for this purpose are described in my application for Letters Patent, Serial 10 No. 578,377, filed July 29, 1922, and in my application for Letters Patent, Serial No. 623,992, filed March 9, 1923. In those structures the blade is held by a holder which is attached to and turnable on the supporting frame. In the construction of the 15 present application, the blade holder is easily detachable from the supporting frame for turning the holder and thereby reversing the blade.

20 In the accompanying drawings,

Fig. 1 is a perspective of a safety razor embodying my improvement, the blade and blade holder having been detached and raised above the working position;

25 Fig. 2 is a perspective of the blade holder;

Fig. 3 is a section on the line, 3—3, of Fig. 1 looking toward the right.

30 Fig. 4 is a section on the line, 4—4, of Fig. 3 looking toward the left;

Fig. 5 is a view similar to Fig. 3, the blade-engaging hooks being given a yielding support;

35 Fig. 6 is a section on the line, 6—6, of Fig. 5, looking toward the left.

Referring to Figs. 1, 2, 3 and 4 of the drawings, A is the usual handle. B is the guard support which rises obliquely from the upper end of the handle. C is the guard. In the form shown in the drawings, the guard is integral with the support, B. D is the blade having a back, D¹, which is engaged in the blade holder, E, which has at each end an arm, E¹, adapted 40 to bear on one side of the back, D¹, and has at the other side an arm, E², adapted to bear on the other side of the back, D¹, about midway between the arms, E¹. On the back of the holder, E, is a handle, E³.

45 On each side edge of the guard, C, is a hook, C¹, extending above and across the upper face of the guard toward the opposite hook, the space between the hook and the upper face of the guard being sufficient 50 to receive the side edge of the blade, D, when the blade lies flatwise on the guard.

On the rear part of the guard is a flexible U-form member, F, having its arms directed toward the forward edge of the guard and secured to the guard by pins or rivets, F¹. 60 On the rear part of each of said arms is a lug, F², which rests against the back of the holder, E, when the holder and blade are in position on the guard. The rivets, F¹, are near the forward ends of the arms of the member, F, and rearward of said rivets the face of the guard is curved downward so as to leave free the part of the member, F, which is rearward of the rivets. On the rear middle part of the member, F, is a handle, F³, adapted to be engaged by the thumb or finger of the operator and pressed downward far enough to lower the lugs, F², sufficiently to allow the holder, E, to be moved rearward in the plane of the blade for the withdrawal of the blade from the guard. When the blade and the holder are to be inserted on the guard, the handle, F³, is similarly pressed downward to allow the holder to pass over the lugs, F². Near the forward edge of the guard, a lug, C², rises from each side edge of the guard in position to bear against the adjacent side edge of the blade when the latter and the holder are in working position. 70

If, during the shaving operation, the blade is to be reversed, the operator depresses the rear part of the member, F, and grasps the handle, E³, and draws the holder and blade backward, in the plane of the blade, until the blade is free from the hooks, C¹. Then he reverses the blade and pushes it forward, in the plane of the blade, under the hooks, C¹, until the blade and the holder again assume the working position, the lugs, F², automatically rising into position behind the holder, E, when the blade and the holder are returned to the working position. 80

As shown in Fig. 3, the bodies of the hooks, C¹, rest throughout their length against the lower face of the guard, C, and are secured to the guard by rivets, C³. 90

In the form shown in Figs. 5 and 6, each hook, C¹, is secured to the guard, C, by rivets placed near the end of the body of the hook, and from those rivets the body of the hook extends downward away from the guard sufficiently to allow upward movement of the hook above the position occupied when the blade, D, is in position under the hook, the 100 110

body of the hook being made flexible to permit upward movement. Stationary lugs, F^4 , are placed on the guard in lieu of the lugs, F^2 , which are supported on the flexible 5 U -form member, F , as above described.

For inserting the blade when the flexible hooks and the fixed lugs are used, the forward edge of the blade is inserted under the hooks, C^1 , and the blade is then pushed 10 forward until it is in the working position, the holder and the rear part of the blade rising to pass over the lugs, F^4 , such rising involving the lifting of the lugs, C^1 , by the blade. When the holder has taken its position in front of the lugs, F^4 , the hooks, C^1 , draw the blade downward against the guard. 15

The blade and the blade back and the blade holder together form a blade structure.

I claim as my invention,

20 1. In a safety razor, the combination of a relatively stationary flat blade-supporting member, a handle on said member, a hook at each side edge of said member, a blade adapted to have either side applied flatwise to said supporting member in engagement with said hooks, releasable means acting away from the handle and being upturned at the rear for engaging the back of the blade and holding it against the supporting 25 member, and a handle extending from the blade parallel to the flat part of said supporting member, substantially as described.

2. In a safety razor, the combination of a relatively stationary flat blade-supporting 30 member, a handle on said member, a hook at each side edge of said member, a blade adapted to have either side applied flatwise to said supporting member in engagement with said hooks, releasable means acting away from the handle and being upturned at the rear for engaging the back of the blade and holding it against the supporting member, and a handle extending from the blade in the plane of the blade, substantially as described. 35

3. In a safety razor, the combination of a relatively stationary flat blade-supporting member, a main handle on said member, a hook at each side edge of said member, a blade adapted to have either side applied flatwise to said supporting member in engagement with said hooks, flexible releasable 40

means acting away from the main handle and being upturned at the rear for engaging the back of the blade and holding it 55 against the supporting member, a holder detachably applied to the blade, and a handle on and parallel to the holder, substantially as described.

4. In a safety razor, the combination of a 60 relatively stationary flat blade-supporting member, a handle on said member, a hook at each side edge of said member, a blade adapted to have either side applied flatwise to said supporting member in engagement 65 with said hooks, releasable means acting away from the handle and being upturned at the rear for engaging the back of the blade and holding it against the supporting member, a holder detachably applied to the 70 blade, and a handle on the holder in the plane of the blade, substantially as described.

5. In a safety razor, the combination of a 75 relatively stationary flat blade-supporting member, means on said member for engaging the side edges of the blade, a blade adapted to have either side applied flatwise to said supporting member, a downward flexible member secured to the supporting 80 member between said member and the blade and extending upward at the back of and against the back of the blade, substantially as described.

6. In a safety razor, the combination of a 85 relatively stationary and flat blade supporting member, a main handle attached to said member, a blade adapted to have either side applied flatwise upon said supporting member, means for releasably engaging the end 90 edges of the blade for holding the blade in such position, and a handle supported by the blade between the ends of the blade and free from the blade supporting member and adapted to be grasped by the hand for removing, turning and replacing the blade on the supporting member, substantially as described. 95

In testimony whereof I have signed my name this 25th day of September, in the 100 year one thousand nine hundred and twenty-three.

WILLIAM G. ADAMS.
